Patented Oct. 19, 1915.

UNITED STATES PATENT OFFICE.

CHARLES W. SULLIVAN, OF LOS ANGELES, CALIFORNIA.

SAFETY ATTACHMENT FOR BOILERS.

1,157,058.

Specification of Letters Patent. Patented Oct. 19, 1915.

Application filed April 21, 1915. Serial No. 22,894.

To all whom it may concern:

Be it known that I, CHARLES W. SULLIVAN, a citizen of the United States, residing at Los Angeles, in the county of Los Angeles and State of California, have invented new and useful Improvements in Safety Attachments for Boilers, of which the following is a specification.

My invention relates to a new and improved safety attachment for boilers and it is an object of my invention to automatically prevent the operation of the injector when the water in the boiler is below a certain predetermined level. As well known, the principal danger in the operation of a boiler is due to the introduction of water when the level of water within the boiler is below the safety level as the sudden generation of steam may cause an explosion of the boiler.

Another object of the invention is to give warning to the engineer by an automatic whistle which is operated when the water level in the boiler falls below the said predetermined level.

Another object of this invention is to automatically close the oil fuel supply to the boiler furnace when the water falls below said level in the boiler.

Another object of this invention is to provide means which will indicate to the engineer in charge that the safety attachment means within the boiler is out of order.

With these and other objects in view which will be apparent as the description proceeds, my invention consists in the construction and arrangement of parts herein-after described and pointed out in the claims.

In the drawings which form a part of this specification, Figure 1 is a side elevation with parts broken away, of a locomotive boiler showing my safety attachment applied thereto. Fig. 2 shows a diagrammatic view of my safety attachment and connections partly in cross section. Fig. 3 is a horizontal section taken on section line 3-3 of Fig. 2.

A locomotive boiler 10 of any desired or preferred construction has mounted on its crown sheet 11 fusible plug 12. I have shown said plug as screwed in crown sheet 11. This plug consists of a tubular metal casing provided with a number of inclined bores 13 arranged around its periphery and leading into the interior thereof. Fusible

metal 14 fills the interior of said plug and covers the openings of bores 13. The fusible metal has a melting point which is above that of any temperatures obtained by the water or steam during the normal operation of the boiler, but should the water level recede below that of the crown sheet and expose the fusible plug to the direct action of the fire, the fusible metal in said plug will be melted and run out of bores 13 thereby establishing communication between the interior of the boiler and the inside of said plug. Secured to the upper part of said plug and extending upwardly therefrom and through the top of the boiler, is a pipe 15 which after leaving the boiler extends rearwardly thereof, then extending downwardly communicates with a tubular valve casing 16. This casing is divided into three chambers. The lower one 17 has mounted therein a cylindrical valve 18 which has a portion cut away on its upper part forming an annular shoulder 19 adapted to coöperate with the annular shoulder 20 formed in the upper part of said chamber 17. The top part of valve 18 is in the shape of an enlarged disk 21 of the same diameter as intermediate chamber 22 of the valve casing. Rigidly secured to valve 18 is a valve stem 23 which extends through the bottom of valve casing 16. A stuffing box 24 secures a fluid tight seal between said stem and said casing. A helical spring 25 is interposed between the bottom of valve casing 16 and the enlarged end of stem 23 holding the valve disk 21 on its seat. Stem 23 projects upwardly from valve body 18 and slidably engages a tubular guide 26 formed in the lower part of a valve 26 which is normally held on its seat by gravity. When valves 21 and 26 are normally seated, stem 23 does not abut against the bottom of said guide, but is positioned some slight distance from it, allowing valve 21 to be raised through said distance without lifting valve 26 from its seat, thus providing a lost motion connection for a purpose to be herein-after described. A pair of air channels 22 establish permanent communication between chamber 22 and the outside air. This valve 26 controls the communication between intermediate chamber 22 and top chamber 27 of the valve casing. Leading from the chamber 27 is a pipe 28 which establishes communication with train line of the air brake system. Leading from the lower part

of intermediate chamber 22 are channels 29-29 leading to pipes 30-30 communicating with injectors 31 of any desired or preferred construction. Interposed between the 5 injectors and pipes 30 are check valves 32 opening toward the side of the injectors. Channels 29 are normally closed by the circular disk 21 but when said valve is lifted from its seat communication between chamber 22 and said channels is established by 10 means of a series of annular bores 34 provided in said disk valve 21. When said valve is normally seated the lower openings of said bores will be closed by the bottom of 15 said intermediate chamber 22. A channel 35 extends from the lower valve chamber 17 and by means of pipe 35' communicates with a whistle 36 of any desired construction. Another channel 37 and pipe 37' leading 20 from the same chamber 17 extend to the oil feed pipe and control a check valve 38 which is adapted to cut off the oil supply to the boiler furnace.

Operation: Assuming that the water level 25 falls below the safety point which, in the present case, is the crown sheet level, the fusible metal in plug 12, being now exposed to the direct heat of the fire, will be melted, running out through bores 13. Communication 30 being now established between the interior of the boiler and the inside of pipe 15, steam will rush through said pipe and enter the lower valve chamber 17 lifting valve 18, the valve disk 21, and valve 26 from their 35 seats, the shoulder 19 contacting with the shoulder 20. The lifting of valve body 18 will uncover the channels leading to whistle 36 and oil valves 38. Steam passing through pipe 35' will blow the whistle 36 while the 40 steam passing into pipe 37' will close oil valve 38, thereby shutting off the oil supply to the fire box. The lifting of valve 26 will establish communication between the train line of the air brake system and intermediate 45 chamber 22 and through bores 34 to channels 29 and pipes 30 will open check valves 32. It will be seen that by opening 32 the injectors 31 will become inoperative for should the engineer in charge, on hearing 50 the alarm whistle 36 blow, start the operation of said injectors, the same will be inoperative because they will fail to raise the water through the water pipe since communication is now established with the 55 atmosphere. The engineer will, therefore, be positively prevented from bringing about the dangerous condition which the sudden introduction of water into a boiler entails when the water therein has sunk below the 60 safety level. Furthermore a reduction of air pressure in the train line is caused by the escape of air therefrom through the opening of valve 26, allowing the air from the train line to pass from chamber 27 to 65 chamber 22 and thence out into the atmos-

phere through channels 22' and into the injector connections 30. Such reduction of pressure in the train line will set the brakes in the train as will be understood. It will therefore be seen that my apparatus automatically applies the brakes in the train, when upon the melting of the fusible plug, the steam lifts valve 26, thereby establishing communication between the train line and intermediate chamber 22.

It may occur that on the locomotive going down a steep grade, the water in the boiler will shift its level so that the water will flow toward the front end of the boiler and the crown sheet in the rear will be uncovered. The safety device will become operative on the melting of the fusible plug. Should now the engineer and the fireman in charge of the locomotive, fearing an instant explosion of the boiler, desert the locomotive and leave the train to its fate, a wreck would be liable to occur, especially in view of the fact that the train is going down a steep grade which is usually found in connection with heavy curves, if it were not for the automatic application of the air brake just described.

The air pressure in the train line is usually about 80 pounds to the square inch. The ordinary working pressure of steam within the locomotive boiler exceeds said pressure, and, therefore, will be able to lift valve 26 against the air pressure in the train line. However, should, for any reason, the steam pressure be below that required to lift valve 26 against the air pressure in the train line, the lost motion connection in the guide 26' will allow valve 21 to be lifted from its seat without affecting valve 26. Atmospheric connection will be established between the injector connections 30 through air channels 22' and bores 34, thus rendering the injectors inoperative, without any connection with the train line.

While I have shown my invention applied to a locomotive boiler, it is obvious that the same is also applicable to stationary boilers of any preferred construction. Where the air brake system is absent, the injectors are made inoperative by providing atmospheric communication with chamber 22 through air channels 22'. On the lifting of valve body 18 and valve disk 21 atmospheric communication will be established with the injectors.

While I have shown my apparatus in connection with a boiler using oil as fuel, it is obvious that the same may be used also where coal is used instead of oil. Where coal is used, pipe 37' is made to extend to and opening into the fire box. In case of 125 said pipe 37' becoming filled with steam from the boiler, on the melting of the fusible plug, the steam from said pipe will extinguish the fire in the furnace.

I have also provided means for detecting 130

whether or not the fusible plug 12 is in its normal condition by providing a small opening 40 in pipe 15 at any suitable point. Assuming that the plug 12 was melted in the previous operation of the boiler and this fact is unknown to the engineer in charge; when the boiler is filled with water and before the same is fired up, the compressed air above the water space will force the water in the boiler which covers said fusible plug through bores 13 or any other leak which may be present, through pipe 15 and the same will run out through the small opening 40, thereby positively indicating to the engineer that the safety attachment within the boiler is out of order.

I do not limit myself to the specific construction of the safety attachment for boilers as described, for it is obvious that changes may be made by those skilled in the art without departing from the spirit of my invention.

I claim:

1. In a safety attachment for boilers the combination of a boiler, a fusible plug mounted on the crown sheet thereof, said plug comprising a tubular casing and adapted to establish communication between the interior of the boiler and the interior of said casing when the water within the boiler falls below a predetermined level, a pipe leading from said plug to the exterior of the boiler, a valve casing mounted on said pipe, a whistle, a fluid fuel supply for the boiler, an injector for the boiler, separate conduits connecting said whistle, said fuel supply and said injector with said valve casing, a check valve disposed in the conduit leading to said fuel supply and adapted to close the same, a check valve disposed in the conduit leading to said injector and adapted to establish communication with a source of air thereby making the injector inoperative, and a valve body within said valve casing normally closing said conduits and adapted to establish communication between the interior of the boiler and said conduits when the fusible plug is melted, whereby said whistle and said check valves will be operated, substantially as described.

2. In a safety attachment for boilers the combination of a boiler, a fusible plug mounted on the crown sheet thereof, a pipe leading from said plug to the exterior of the boiler, said plug being adapted to establish communication between the interior of the boiler and the interior of said pipe when the water within the boiler falls below a predetermined level, a valve casing mounted on said pipe, a fluid fuel supply for the boiler, an injector for the boiler, separate conduits connecting said fluid fuel supply and said injector with said valve casing, a check valve disposed in the conduit leading to said fuel supply and adapted to close the

same; a check valve disposed in the conduit leading to said injector and adapted to establish communication with a source of air, thereby making the injector inoperative, and a valve body within said valve casing normally closing said conduits and adapted to establish communication between the interior of the boiler and said conduits when the fusible plug is melted, whereby said check valves will be operated, substantially as described.

3. In a safety attachment for boilers the combination of a boiler, a fusible plug mounted within the boiler, a pipe leading from said fusible plug to the exterior of the boiler, said plug being adapted to establish communication between the interior of the boiler and the interior of said pipe when the water within the boiler falls below a predetermined level, a valve casing mounted on said pipe, an injector for the boiler, a conduit connecting said injector with said valve casing, a check valve disposed in said conduit and adapted to establish communication with a source of air, thereby making the injector inoperative, and a valve body within said valve casing normally closing said conduit and adapted to establish communication between the interior of the boiler and said conduit when the fusible plug is melted, substantially as described.

4. In a safety attachment for boilers the combination of a boiler, a fusible plug mounted on the crown sheet thereof, a pipe leading from said plug to the exterior of the boiler, said plug being adapted to establish communication between the interior of the boiler and the interior of said pipe when the water within the boiler falls below a predetermined level, a whistle, a fluid fuel supply for the boiler, an injector for the boiler, separate conduits connecting said whistle, said fuel supply, and said injector with said pipe, a check valve disposed in the conduit leading to said injector adapted to establish communication with a source of air, thereby making the injector inoperative, a check valve disposed in the conduit leading to said fuel supply and adapted to close same, and means normally closing said conduits and adapted to establish communication between the interior of the boiler and said conduits when the fusible plug is melted, whereby said whistle and said check valves will be operated, substantially as described.

5. In a safety attachment for boilers, the combination of a boiler, a fusible plug mounted on the crown sheet thereof, a pipe leading therefrom to the exterior of the boiler, said plug being adapted to establish communication between the interior of the boiler and the interior of said pipe when the water within the boiler falls below a predetermined level, a valve casing mounted on said pipe, a whistle, a fluid fuel supply for

the boiler, an injector for the boiler, means within said valve casing operative when the fusible plug is melted to operate the whistle, to shut off the fuel supply, and to render the injector inoperative, substantially as described.

6. In a safety attachment for boilers the combination of a boiler, a fusible plug mounted on the crown sheet thereof, a pipe 10 leading therefrom to the exterior of the boiler, said plug being adapted to establish communication between the interior of the boiler and the interior of said pipe when the water within the boiler falls below a predetermined level, a fluid fuel supply for the boiler, an injector for the boiler, means mounted on said pipe for shutting off said fuel supply and for rendering said injector inoperative, an outlet in said pipe adapted 15 to allow the water from the boiler to flow from said pipe when the fusible plug is melted and the boiler is filled with water previous to firing up, substantially as de- 20 scribed.

7. In a safety attachment for locomotive 25 boilers, a fusible plug mounted in a boiler, a pipe leading therefrom to the exterior of the boiler, said plug being adapted to establish communication between the interior of the boiler and the interior of said pipe 30 when the water within the boiler falls below a predetermined level, a water feeding apparatus for the boiler, and means operative when the fusible plug is melted for rendering said water feeding apparatus inoperative, substantially as described.

8. In a safety attachment for locomotive boilers, the combination with a boiler and a water feeding apparatus for the boiler, means operative when the water within the 40 boiler falls below a predetermined level for rendering said water feeding apparatus inoperative, substantially as described.

In witness that I claim the foregoing I have hereunto subscribed my name this 3rd 40 day of April, 1915.

CHARLES W. SULLIVAN.
